LAZY SUSAN DISPENSER

Einar G. Ahlman, Box 16, Rte. 307, Austintburg, Ohio
Filed Mar. 17, 1964, Ser. No. 352,512

8 Claims. (Cl. 211—69)

This invention relates to a novel and useful Lazy Susan and more specifically to an apparatus of the Lazy Susan type designed primarily for use on a desk and to support numerous types of writing equipment and accessories. However, it is to be noted that the Lazy Susan of the instant invention could also be utilized to advantage in other environments and for supporting numerous other types of articles.

The Lazy Susan of the instant invention includes a base to which the lower end of an upstanding post is secured. A turntable is rotatably mounted on the post with a thrust bearing disposed between the lower end of a turntable and the base. The turntable includes numerous tray-like compartments that are disposed circumferentially thereabout in two vertically spaced sets of compartments and also various other types of circumferentially spaced compartments.

The main object of this invention is to provide an apparatus of the Lazy Susan type adapted for use in various environments wherein it is advantageous to have a plurality of readily accessible compartments for storing a plurality of different kinds of articles.

Another object of this invention is to provide a Lazy Susan in accordance with the preceding object which is specifically adapted to support writing equipment and accessories such as those found about a desk.

Another object of this invention is to provide a Lazy Susan that has a pleasing appearance.

A final object of this invention to be specifically enumerated herein is to provide a Lazy Susan in accordance with the preceding objects which will conform to conventional forms of manufacture, be of simple construction and easy to use so as to provide a device that will be economically feasible, long-lasting and relatively troublefree in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the Lazy Susan of the instant invention;

FIGURE 2 is an enlarged vertical sectional view taken substantially upon a plane passing through the center of the Lazy Susan; and

FIGURES 3 and 4 are horizontal sectional views taken substantially upon the planes indicated by the section lines 3—3 and 4—4, respectively, of FIGURE 2.

Referring now more specifically to the drawings, the numeral 10 generally designates the Lazy Susan of the instant invention. The Lazy Susan 10 includes a generally circular base 12 to which the lower end of an upright post 14 is secured. A turntable generally referred to by the reference numeral 16 is provided and includes a conical core 18 having an upstanding bore 20 formed therethrough which snugly receives the post 14 thereby rotatably mounting the turntable 16 on the post 14. In addition, it may be seen that a thrust bearing 22 including an upper race 24 and a lower race 26 separated by means of a plurality of anti-friction balls 28 is provided and disposed about the post 14 between the lower end of the core 18 in the base 12.

The turntable 16 includes an outer sleeve portion 30

2

whose lower end is secured to and supported from a plurality of generally radially outwardly projecting upstanding partition members 32 spaced circumferentially about the lower end of the core 18. The lower end of the core 18 includes an outwardly projecting and generally annular flange 34 including portions extending beneath the lower end of the sleeve portion in vertically spaced relation thereto and projecting outwardly beyond the outer surfaces of the sleeve portion 30. From FIGURES 1 and 2 of the drawings it may be seen that the flange 34 curves outwardly and upwardly at its outer marginal portions and that the partition members 32 divide the tray formed by the flange 34 into a plurality of tray segments, each defining a storage area in communication with the area disposed between the core 18 and the sleeve portion 30 disposed thereabove.

From FIGURE 2 of the drawings it may be seen that the sleeve portion 30 includes a second outwardly projecting and generally annular flange 36 which is substantially identical to the flange 34 but which is somewhat larger in diameter. In addition, a plurality of generally radially extending partition members 38 are carried by the flange 36 and spaced circumferentially thereabout. Further, the partition members 38 correspond to the partition members 32 and have the lower end of an outer sleeve member 40 secured thereto for support therefrom. The outer sleeve member 40 is similar to the sleeve portion 30 and it may be seen from FIGURE 2 of the drawings that a top closure wall 42 which is centrally apertured as at 44 is provided and is secured to the upper end of the post 14 which is externally threaded as at 46 by means of a knob 48 having a threaded bore 50 formed therein. The knob 48 is threadedly engaged on the externally threaded portion 46 of the post 14 and an anti-friction washer 52 is disposed between the confronting surfaces of the knob 48 and the closure wall 42.

The second annular outwardly projecting flange 36 has a plurality of small openings 54 formed in portions thereof and the portions of the closure wall 42 disposed above the openings 54 are provided with openings 56 in alignment with the openings 54. The openings 56 are each larger in diameter than the openings 54 and the latter are adapted to receive the pointed ends 58 of pencils 60 passed downwardly through the opening 56 formed in the closure wall 42. Each of the segments formed between adjacent walls of the partition members 32 and 34 is in communication with the storage area disposed immediately thereabove defined by the corresponding sleeve portion 30 or sleeve member 40 and may be utilized to support various types of articles.

From FIGURE 2 of the drawings, it will be noted that the outer sleeve member 40 includes extended portions 62 which project down into each tray segment having the openings 54 formed therein. In this manner, a closed compartment 64 is formed above each apertured tray segment.

In operation, the pencils 60 may be supported in the manner illustrated in FIGURE 2 of the drawings together with pens and other similar articles while various other types of writing equipment and accessories may be supported from the plurality of tray segments defined by the flanges 34 and 36.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A Lazy Susan comprising a base, an upstanding turntable means rotatably mounted on said base, thrust bearing means disposed between said base and the lower end of said turntable means, said turntable means including an upstanding center core and an outer sleeve portion disposed about said core and defining a vertically elongated annular storage area between said core and said sleeve portion, a plurality of generally radially extending and upstanding partition members secured between said core and sleeve portion at points spaced circumferentially about said storage area and dividing the latter into a plurality of segments, said sleeve portion terminating at its lower end above the portions of said base disposed therebeneath, said core including an outwardly projecting generally annular flange including portions extending beneath the lower end of said sleeve portion in vertically spaced relation thereto and projecting outwardly beyond the outer surfaces of said sleeve portion.

2. The combination of claim 1 wherein at least some of said segments are provided with closure walls at their upper ends extending between said core and the corresponding portions of said sleeve portion and between corresponding partition members of said Lazy Susan.

3. The combination of claim 1 wherein said generally annular flange curves upwardly and outwardly at its outer marginal portions.

4. The combination of claim 1 wherein an outer sleeve member is disposed about said sleeve portion and defines a second vertically elongated annular storage area between said sleeve portion and said sleeve member, a plurality of generally radially extending partition members secured between said sleeve portion and said sleeve member at points spaced circumferentially about said second storage area and dividing the latter into a plurality of compartments, said sleeve portion including a second generally annular outwardly projecting flange including portions extending beneath the lower end of said sleeve member in vertically spaced relation to the latter and projecting outwardly beyond the outer surfaces of said sleeve member.

5. The combination of claim 4 wherein said second annular flange curves upwardly and outwardly at its outer marginal portions.

6. The combination of claim 1 wherein an outer sleeve member is disposed about said sleeve portion and defines a second vertically elongated annular storage area between said sleeve portion and said sleeve member, a plurality of generally radially extending partition members secured between said sleeve portion and said sleeve member at points spaced circumferentially about said second storage area and dividing the latter into a plurality of compartments, said sleeve portion including a second generally annular outwardly projecting flange including portions extending beneath the lower end of said sleeve

member in vertically spaced relation to the latter and projecting outwardly beyond the outer surfaces of said sleeve member, at least some of said compartments being provided with closure walls at their upper ends extending between said sleeve portion and said sleeve member and partition members.

7. The combination of claim 1 wherein an outer sleeve member is disposed about said sleeve portion and defines a second vertically elongated annular storage area between said sleeve portion and said sleeve member, a plurality of generally radially extending partition members secured between said sleeve portion and said sleeve member at points spaced circumferentially about said second storage area and dividing the latter into a plurality of compartments, said sleeve portion including a second generally annular outwardly projecting flange including portions extending beneath the lower end of said sleeve member in vertically spaced relation to the latter and projecting outwardly beyond the outer surfaces of said sleeve member, at least some of said compartments being provided with closure walls at their upper ends extending between said sleeve portion and said sleeve member and partition members, said second annular flange curving upwardly and outwardly at its outer marginal portions.

8. The combination of claim 1 wherein an outer sleeve member is disposed about said sleeve portion and defines a second vertically elongated annular storage area between said sleeve portion and said sleeve member, a plurality of generally radially extending partition members secured between said sleeve portion and said sleeve member at points spaced circumferentially about said second storage area and dividing the latter into a plurality of compartments, said sleeve portion including a second generally annular outwardly projecting flange including portions extending beneath the lower end of said sleeve member in vertically spaced relation to the latter and projecting outwardly beyond the outer surfaces of said sleeve member, at least some of said compartments being provided with closure walls at their upper ends extending between said sleeve portion and said sleeve member and partition members, said second flange having openings formed therein adapted to receive the pointed ends of pencils, the last-mentioned closure walls including some portions having openings formed therein in alignment with the first-mentioned openings.
